Jefferson, Clevenger & Gable, ATTORNEYS.

UNITED STATES PATENT OFFICE

CHARLES J. JEFFERSON, OF SPRINGFIELD, MASSACHUSETTS, ASSIGNOR TO J. STEVENS
ARMS COMPANY, A CORPORATION OF MASSACHUSETTS

FIREARM

Application filed February 11, 1930. Serial No. 427,481.

The object is to improve the construction of fire arms which are hinged to break open at the breech for loading; more specifically to improve the mechanism which serves to lock the gun closed; and still more specifically to utilize this mechanism as a means of guiding or supporting the hammer mechanism, thereby simplifying the construction and economizing labor and weight. Heretofore it has been customary to maintain the alignment between the hammer, and its spring or spring plunger, by means of special abutment faces provided inside the receiver or frame. According to this invention these abutments may be eliminated, and this customary function of such abutments is performed by the link which forms the operating connection between the top-snap or thumbpiece and the locking bolt. Such link for this purpose is now designed as a yoke or two-limbed member embracing or enclosing the hammer and the spring plunger on both sides, and effectually preventing displacement of the latter and at the same time permitting the practical employment of a plunger head which produces a desirable rebound effect independently of the trigger, as presently disclosed. Adjustment of the position of the top-snap or thumbpiece is secured by a thread bolt on the locking-bolt or latch.

In the accompanying drawings, Fig. 1 is a sectional elevation at the frame of a break-down shot gun embodying my invention. Fig. 2 is a plan view of the same gun. Fig. 3 is a horizontal section on approximately the broken line 3—3 of Fig. 1. Fig. 4 is another sectional elevation at frame of the same gun, but showing the gun open and the locking mechanism in unlocked position. Fig. 5 is a detail of the actuator for the yoke or locking bolt link, the parts being shown disassembled for clarity of illustration. Fig. 6 is a perspective of the yoke.

The drawings illustrate the invention applied to a conventional type of break-down shot gun. The hollow frame or receiver 1 is attached to the stock 2 as usual, and the barrel 3 is hinged on the cross bolt 5 to the forward end of the frame, so that the gun

may be opened as usual. The ejector 7, locking bolt keeper 8 on the rear end of the barrel, and the firing pin 9 will be recognized. The hammer 12 is pivoted in the frame at 13, projecting at its upper end through a longitudinal slot 14 in the top of the frame 1. The cocking notch for the hammer is at 15, and the notch for half-cocked at 16. The trigger 17 is pivoted in the trigger plate or lower wall of the frame 1 in the usual manner, and as usual its spring 18 urges its upper end into engagement with the hammer. The hammer spring 21 is carried on a plunger 22 telescoping with a sleeve 23, which is seated by its pointed end 24 upon the rear wall of the receiver. The plunger head 25 bears against the hammer 12, being unattached to it, and has its heel portion so arranged that after firing it restores the hammer automatically to the position shown in Fig. 1, in which the trigger engages the half-cock notch 16.

The locking member is a bolt or a latch 28, hung at 27 between the side walls of the receiver and so arranged that its lower end snaps into engagement with the arc-shaped seat of the keeper 8 to hold the gun closed. The locking bolt is coupled to its operator, the thumb-lever or top snap 29 at the top of the frame, by means of the special connecting link or yoke 30 above referred to and which is separately shown in Fig. 6. This yoke may be formed from sheet metal if desired and is connected to the top snap hub or pivot 31 through the agency of a disc 32 sleeved on the hub with a notch 33 to receive a lug 34 formed on the lower edge of the yoke, see Figs. 5 and 6, the sleeved disc being secured non-rotatably to the end of pivot 31 as plainly shown in Fig. 5. The screw 36 holds the sleeved disc in place on the hub and the disc holds the yoke on the hub between itself and the top wall of the receiver. Rotation of the top snap thus reciprocates the yoke upon the sleeve which it fits snugly, and thereby actuates the bolt 28 to which the arms of the yoke are pivoted by screws, 37. In this manner the yoke link 30 is safely retained against sidewise movement, that is, by its engagement with the locking bolt 28 and by its

engagement with the disc sleeve which it embraces. The front and rear parts of the yoke link are relatively offset, the front end being low to pass under the hammer pivot pin 13 and the rear being higher for connection to the top snap. The oblique middle part, marked 38, flanks the plunger head 25 and in such close proximity thereto on both sides as to forestall any possibility of its lateral displacement relatively to the hammer. By this means, any need of internal abutment faces on the frame 1, to guide the hammer spring, is done away with as of course the machining thereof which is a costly operation, and the plunger head 25 may be fitted to the hammer so as to hold it normally in half-cock position without being fastened to the hammer.

The spring 39 urges the yoke link and locking bolt 28 forward, and the top snap lever toward the locked or center position. The limit of this movement is determined by the set screw 40, carried by the locking bolt 28, and which strikes the lip or wall 41 of the frame, and by the adjustment of such screw the locking bolt 28 is made to come to its correct resting place on the locking bolt keeper 8.

I claim:

1. In a firearm, the combination with the frame, a barrel hinged to the frame on a horizontal axis, a hammer pivoted to the frame, and hammer-spring means bearing against the hammer, of locking means to lock the barrel in firing relation to the frame and confine the hammer spring on the hammer, said means including a lock-operating yoke within the frame extending rearwardly from adjacent the rear end of the barrel and passing close to the hammer-spring means at both sides thereof adjacent the bearing of the hammer-spring means on the hammer.

2. In a firearm, the combination with the frame, a barrel hinged to the frame on a horizontal axis, a hammer pivoted within the frame, a hammer-spring plunger, the head of which bears against the hammer, and a coiled hammer-spring surrounding the plunger, of locking means to lock the barrel in firing relation to the frame and confine the hammer-spring plunger head to the hammer, said means including a yoke within the frame extending rearwardly from adjacent the rear end of the barrel, and passing on both sides of and close to the said plunger head.

3. In a firearm, the combination with the frame, a barrel hinged to the frame on a horizontal axis, a hammer pivoted to the frame, and hammer-spring means bearing against the hammer to hold it in partly-cocked position, of a locking means to lock the barrel in firing relation to the frame and confine said hammer-spring means on the hammer, said locking means including a lock-operating yoke within the frame extending rear-

wardly from adjacent the rear end of the barrel, and passing on both sides of the hammer and flanking the hammer-spring means at both sides thereof adjacent its bearing on the hammer.

4. In a firearm, the combination with the frame, a barrel hinged to the frame on a horizontal axis, and a hammer pivoted within the frame, of a locking bolt hinged within the frame to lock the barrel in firing relation to the frame, an operating link therefor extending rearwardly from said bolt, a finger piece external of the frame connected to said link, and adjustable means cooperating with the locking bolt to limit the movement of the locking bolt in the locking direction.

5. The subject matter of claim 4, characterized by the fact that said adjustable means is a threaded bolt carried by the locking bolt and the threaded bolt is arranged to strike a part carried by the frame to limit the movement of the locking bolt in the locking direction.

6. In a firearm, the combination with the frame, a barrel hinged thereto, and a hammer pivoted within the frame, of a locking bolt hinged within the frame to lock the barrel in firing relation to the frame, a pivoted top snap lever on the top wall of the frame, and a yoke link extending under the hammer pivot with the ends of its two arms pivotally attached to said bolt and its other end embracing the hub of said lever, and held thereby against said frame top wall.

7. In a firearm, the combination with the frame, a barrel hinged to the frame on a horizontal axis, a pivoted hammer within the frame, of hammer-spring means bearing against the hammer, a locking bolt for the barrel, a yoke extending rearwardly therefrom below the hammer pivot and thence toward the top wall of the frame, the middle portions of the two arms of the yoke lying at opposite sides of said hammer-spring means, and a finger lever on the top wall of the frame connected to reciprocate said yoke to operate the locking bolt.

8. The subject matter of claim 7, characterized by the fact that there is a spring between the rear portion of the yoke and the rear of the frame to move the locking bolt to locking position.

In testimony whereof, I have signed this specification.

CHARLES J. JEFFERSON.
